United States Patent Office.

ALBERT G. BREWER, OF WASHINGTON, DISTRICT OF COLUMBIA.

Letters Patent No. 70,158, dated October 29, 1867.

IMPROVED LEATHER-QUILTING MACHINE.

The Schedule referred to in these Letters Patent and making part of the same.

Be it known that I, ALBERT G. BREWER, of the city and county of Washington, District of Columbia, have invented a new and useful improvement on the "Quilting Machine" for inserting steel or other wires into Leather; and I do hereby declare that the following is a full, clear, and exact description thereof, which will enable others skilled in the art to make and use the same, reference being had to the accompanying drawings, forming part of this specification.

The present invention relates to a machine to be used for inserting steel or other wires therein, the object being to increase the wear and durability of the leather; and the invention relates to or consists in a novel arrangement of mechanical devices, whereby the leather is fed through the machine so as to cause the wire to be forced into the leather by the die, as will be shown by the detail description of the machine, reference being had to the accompanying plate of drawings, in which—

Figure 1 is a side view.

Figure 2 is an end view (drawn full size) of the slide plate and working parts.

Figure 3 is a vertical view of the bed-piece.

Figure 4 is a view of the slide and die.

Figure 5 is a view of the wire-feeder.

Figure 6 is a view of the adjusting slide.

Fig. 1. A A represents the bed-piece on which the machine rests. B B is an arm bolted on to the bed-piece A A, reaching nearly across the bed-piece, and supporting the principal working parts. C is a pulley, where the power is applied to drive the machine. D is the main shaft, having on the end D' a crank to drive the slide F, which has connected to it the die and wire-feeder. G is the feed-wheel, and is keyed to the shaft v, which is turned by the lever I, connected to the eccentric J, it having a pawl, K, and spring L, working into the ratchet-wheel H, causing the shaft to revolve a certain distance at each revolution of the shaft D. M is a friction-screw, keeping the eccentric stationary on the shaft D. When the machine is at work, the feed-wheel G presses the leather up against the end of the slide-plate K, where the wire is forced into it. The feed-wheel G is pressed up under the leather by a lever working under the shaft v at S, having a suitable weight attached to its opposite end. N is the wire-regulator, causing the wire forced into the leather to be longer or shorter, as required. An end view is shown in fig. 2, and side view, full size, in fig. 6. This is made to slide out or in by the nut O working between the slide-plate E and post o. Q is a friction-bolt, for keeping the wire in its place after being fed to the cutter. P is a screw, used to keep a piece of steel that is dove-tailed into the slide-plate E in its place. This piece of steel is where the die and cutter work, and is shown in fig. 2 by dotted lines 1 1. Fig. 2 is a front view of the slide-plate and working parts. M M are plates screwed on to the slide-plate E, and keep the slide F in its place. D' represents the end of the shaft D, having the crank-wrist V working in the slot in the slide F, and causing it to work the die s, shown in fig. 4. At the upper end of the die is a stud, b, which keeps the die in its place, and when the die becomes shortened by wear can be lengthened by turning the stud, which has a slot in its end for the inserting of a screw-driver. N represents an end view of the wire-adjuster. It has a piece of steel fastened on its side by screws, which is narrower at the inner end, as represented in fig. 6, its purpose being shown in a description of the working of the machine. c is a steel spindle running through the slide F, and has a spring, e, connected with it. A side view is shown in fig. 5. The wire to be fed to the cutter passes through the hole n in the spindle c. The pin f is to keep the spindle from turning round too far when at work. i is an inclined plane on the slide F, which works the lever W. The lever works on the pin i; its use is to work the slide-cutter X, which cuts the wire at each revolution of the shaft D. a is a spring, used to move the cutter X back after having done its work. b is a pin in the cutter that the spring works against. Y is a bolt, screwed through the lever W, and has a pinch-nut to keep it in its place. The object of this is to push the cutter its proper distance as it becomes shorter by use, the bolt being screwed through the lever further. T represents the wire to be cut and driven.

The operation of the machine is this: In fig. 2 the crank is represented at one-fourth stroke. It will be seen that the spring e is nearly in contact with the wire-regulator plate d, when the slide F moves down so that the spring e touches the wire-regulator d. It being a little too long to pass by the plate d without springing, it will cause the spindle c to turn a little, and the hole n in the spindle c, shown in fig. 1, being only a little larger

than the wire, it will jam the wire so as to cause it to pass down with the slide F till the spring e passes the plate d; it then releases its hold. The hole n does not run exactly in the same direction as the wire, but so that when the slide is returning it will not jam the wire, but let it pass through the hole n freely. When the slide F moves up about half its distance, the end of the lever W comes in contact with the inclined plane i, causing the cutter X to cut and move the wire fed down under the die ready to be forced into the leather. When this is done it will be seen that the crank is at its top centre. When the slide F has been drawn to where it is represented in fig. 2, the cutter will have been drawn back by the spring a, and the die will have commenced to push the wire cut down to be forced into the leather.

I claim as new, and desire to obtain by Letters Patent—

The combined arrangement of the spindle e, adjusting-slide N, and plate d, the adjusting-bolt Y, and adjusting-stud h, arranged substantially as and for the purpose described.

ALBERT G. BREWER.
